SETH A. CRONE, OF EAST ORANGE, NEW JERSEY.

BRAKE-BEAM FOR RAILWAY-CARS.

1,073,220.

Specification of Letters Patent. Patented Sept. 16, 1913.

Application filed January 20, 1913. Serial No. 743,043.

To all whom it may concern:

Be it known that I, SETH A. CRONE, a citizen of the United States, and a resident of East Orange, in the county of Essex and State of New Jersey, have invented certain new and useful Improvements in Brake-Beams for Railway-Cars, of which the following is a specification.

The invention relates to improvements in brakes for railway cars and the like, and it consists in the novel features and structure hereinafter described and particularly pointed out in the claims.

The invention pertains more particularly to brake-heads adapted to carry the brake-shoes and to the special means I provide for adjustably securing said heads on grooved sleeves arranged on the ends of brake-beams.

The main object of the present invention is to provide a very durable brake-head lacking complexity and capable of being adjustably secured to the beam by very durable and inexpensive means adapted to the groove in the sleeve on which the brake-head is mounted.

The invention will be fully understood from the detailed description hereinafter presented, reference being had to the accompanying drawings, in which:

Figure 1 is a side elevation of a portion of one end of a brake-beam having thereon a grooved sleeve, brake-head and securing means embodying my invention; Fig. 2 is a vertical section through the same on the dotted line 2—2 of Fig. 1; Fig. 3 is a detached face view of a key employed in accordance with my invention for securing the brake-head upon the beam; Fig. 4 is an edge view of the same; Fig. 5 is a vertical section, partly broken away, through a brake-head and securing means embodying a modification of my invention. Fig. 6 is a rear elevation of a brake-head embodying a further modification of my invention; Fig. 7 is a vertical section through the same on the dotted line 7—7 of Fig. 6, and shows in section the usual grooved sleeve on which the brake-head is mounted; Fig. 8 is a detached rear face view of the securing key employed in the construction shown in

Figs. 6 and 7, and Fig. 9 is an edge view of the same.

In the drawings, referring to Figs. 1 to 4 inclusive, 10 designates the brake-head as a whole, and this head with the exception of the features embracing my invention may be of customary or any suitable form and construction. The brake-beam is numbered 11 and the sleeve thereon 12, said sleeve being formed with a circumferential groove 14 extending partly or entirely around the same, as usual, and receiving the head 10 in a manner well understood.

The brake-head 10 is preferably formed integrally with a back-portion 15 which by preference is open at its center, as at 16, and said head has at the upper end of said portion 15 a vertical transverse slot or opening 17 and at the lower end of said portion a corresponding transverse slot or opening 18 for a key or strip 19 whose middle portion enters the groove 14 and firmly bearing against the sleeve 12 effects the securing of the head on the beam. The key 19 may be in the form of a flat strip of strong spring metal, as represented in Figs. 3 and 4, and at its upper end said strip will be apertured, as at 20, to receive a securing bolt 21.

The back portion of the head 10, adjacent to the upper or entrance slot 17, is formed with a downwardly and outwardly inclined member 22 affording a wall or seat against which the upper end of the key 19 may be flexed and secured by means of the bolt 21 and nut 23 thereon. The back wall of the lower slot 18 preferably inclines downwardly and forwardly so as to deflect the lower end of the key 19 downwardly and forwardly. The lower slot 18 preferably inclines downwardly through the slots 17, 18 and thereby flexes the key 19 and cause its middle portion to bind against the sleeve 12.

After the head 10 has been placed on the sleeve 12 and the key 19 driven downwardly into the slots 17, 18 and against the said sleeve, said key is additionally flexed against the sleeve by having its upper portion forced forwardly against the member 22 by means of the bolt 21 and nut 23. The member 22 serves to receive the bolt 21 and

as a bearing for the upper portion of the key 19, and the nut 23 when screwed inwardly on the bolt 21 and against the key gradually forces the upper portion of the 5 key against said member. The plain flat flexed strip or key 19 is capable of effectually securing the head 10 on the sleeve 12, and the bolt and nut afford very simple and convenient means for flexing the strip or 10 key and holding the same in its flexed condition. The slot 17 is wider at its upper than at its lower end, being approximately wedge-shaped, and hence the upper portion of the key may be moved forwardly against 15 the flat face of the member or, by loosening the nut 23, allowed to recede therefrom.

I preferably secure some flexing of the key 19 by the drive of the latter into the slots 17, 18 and then attain the additional 20 flexing of the key required by means of the bolt 21 and nut 23, but I may when desired apply a bolt and nut to each end of the key and by means of the same flex both ends of the key forwardly, as shown in 25 Fig. 5, in which, being a modification, I number the head 30, the sleeve 31, the key 32, and the upper and lower key-slots 33, 34 respectively. The head 30 adjacent to the upper slot 33 is formed with a bearing 30 member 35 against which by means of a bolt 36 and nut 37, the upper end of the key 32 may be flexed and held, and said head adjacent to the lower slot 34 is formed with a corresponding member 38 against 35 which by means of a bolt 39 and nut 40, the lower end of the key 32 may be flexed and held. The construction shown in Fig. 40 will be readily understood without further detailed explanation, and it will be seen that the plain key 32 when held flexed against the sleeve by a bolt and nut at each end may be relied upon to securely hold the head.

The opening 16 in the back of the head 45 10 and the corresponding opening 41 in the head 30 admit of the middle portions of the keys being readily inspected and also, when necessary, of the head being secured on a sleeve or end of a beam not possessing 50 an annular groove 14 to house the middle portion of the key. The openings 16, 41 will preferably be of about the same width as the groove in the sleeve and slightly greater in width than the key, as may be 55 understood by reference to Fig. 1.

In respect to that embodiment of my invention employing a spring-key, I do not confine the invention to details of construction further than may be rendered necessary by my claims, the essential consideration being that the plain independent strip or key at one end shall bear against the head and at its middle portion against the part on which the head is secured and that

means, as a bolt and nut, shall be provided 65 adjacent to at least one end of the key for enabling the key to be conveniently and to the requisite degree flexed.

In one form of my invention which I illustrate in Figs. 6 to 9 inclusive, I substitute for the spring securing key shown in Figs. 3 and 4 a substantially rigid securing key 42. The brake-head shown in Figs. 6 and 7 is numbered 43 and it has a lower opening 44 in its back for the lower 70 end of the key 42 and an upper member 45 for a bolt 46 which passes through the same and a hole 47 in the upper end of the key 42 and receives a nut 48 by which the upper end of the key may be firmly forced to- 75 ward the member 45 and the middle portion of the key effectually bound against the sleeve 49 on which the head 43 is mounted. The frontwardly facing wall of the opening 44 is convexed and the rear face of the 80 lower end of the key 42 is concaved to fit and obtain a firm bearing against said wall, as shown in Fig. 7. The key 42 is slightly 85 concave on its front face where it engages the sleeve 49 for the purpose of permitting 90 a reasonably extended surface of the key to bind against said sleeve. The key 42 is slightly less in width than the groove 50 in the sleeve 49, and when on the head 43 said key lies between two flanges 51 formed 95 on said head and is exposed at its back except at its lower end which is partly concealed behind the transverse bar or member 52, against which the lower end of the key has a firm bearing. The key 42 is provided 100 with edge stiffening and strengthening flanges 53 and said key is a substantially rigid structure, although capable of limited flexion under the pressure of the nut 48, as distinguished from a spring or flexible 105 key. It has been found that in some instances a substantially rigid key, as 42, is preferred but in general the spring key, as 19, has proven to be satisfactory. The head 43 is not only open at upper and lower 110 sides of its back but by preference is open entirely at its back except at the transverse bar 52.

What I claim as my invention and desire to secure by Letters Patent, is:

1. In a brake-beam, the combination with a brake-head open at upper and lower sides of its back, a part of the beam on which said head is mounted, an independent normally substantially straight spring key in said 120 back and bearing at an intermediate portion against said part and at one end against said back, and means for flexing the key and holding it in its flexed condition.

2. In a brake-beam, the combination with a brake-head open at upper and lower sides of its back, a grooved sleeve on said beam and on which said head is mounted, a nor-

5 mally substantially straight spring key in said back and at an intermediate portion being within the groove of and bearing against said sleeve and at one end bearing against said back, and means for flexing the key and holding it in its flexed condition.

10 3. In a brake-beam, the combination with a brake-head open at upper and lower sides of its back, a part of the beam on which said head is mounted, an independent normally substantially straight spring key in said back and bearing at an intermediate portion against said part and at one end against said back, and means for flexing the 15 key and holding it in its flexed condition, said means comprising a bolt extended through a portion of said head and the end of said key and a nut on said bolt for forcing said end of said key toward said portion of said head.

20 4. In a brake-beam, the combination with a brake-head having at upper and lower sides of its back transverse slots and adjacent to one of said slots an integral member extending beyond and forwardly thereof, a part of the beam on which said head is mounted, a normally substantially straight spring key in said slots and bearing at an intermediate portion against said part, and 25 means for flexing the key and binding an end portion thereof in relation to said member.

30 5. In a brake-beam, the combination with a brake-head having at upper and lower sides of its back transverse slots and adjacent to one of said slots an integral member extending beyond and forwardly thereof, a part of the beam on which said head is mounted, a normally substantially straight 35 spring key in said slots and bearing at an intermediate portion against said part, and means for flexing the key and binding an end portion thereof in relation to said member, said means comprising a bolt extended through said member and the end of said key and a nut on said bolt for forcing said end of said key against said bearing surface.

40 6. In a brake-beam, the combination with a brake-head having at upper and lower sides of its back transverse slots, a part of the beam on which said head is mounted, an independent normally substantially straight spring key in said slots and bearing at an 45 intermediate portion against said part, and means for flexing the key and holding it in its flexed condition, said head at the middle portion of its back being open in line with the key.

50 7. In a brake-beam, in combination, an adjustable brake-head having at upper and lower sides of its back transverse slots, a part on which said head is mounted, a normally substantially straight spring key

flexed by its drive into said slots and bearing at an intermediate portion against said part, and means for increasing and controlling the flexing of said key. 65

8. In a brake-beam, in combination, an adjustable brake-head having at upper and lower sides of its back transverse slots, a part on which said head is mounted, a normally substantially straight spring key flexed by its drive into said slots and bearing at an intermediate portion against said part, and means for increasing and controlling the flexing of said key, said means comprising a bolt extended through a portion of said head and the end of said key and a nut on said bolt for forcing said end of said key toward said portion of said head. 70 75

9. In a brake-beam, the combination with a brake-head having in its back a transverse opening to slip over the end of the beam and rearwardly of said opening and between the integral sides of said head a vertical opening communicating with said transverse opening, a part of the beam on which said head is mounted, an independent substantially vertical key in the back of said head extending along said vertical opening and at its middle portion bearing against said part of said beam, means engaging one end of said key, and means for forcing the other end of said key transversely toward the adjacent forward part of said head and securing it and comprising a bolt extended through a portion of said head and said key and a nut on said bolt for forcing said end of said key toward said part of said head. 85 90 95 100

10. In a brake-beam, the combination with a brake-head having a slot in a portion of its back the forwardly facing wall of which slot affords a fixed bearing, a part of the beam on which said head is mounted, 105 an independent substantially vertical key in the back of said head fulcrumed at one end on said bearing and at its middle portion bearing against said part of said beam, and means for forcing the other end of said key 110 transversely toward the adjacent part of said head. 110

11. In a brake-beam, the combination with a brake-head having a slot in the lower portion of its back, the forwardly facing wall 115 of which slot affords a fixed bearing, a part of the beam on which said head is mounted, an independent substantially vertical key in the back of said head fulcrumed at its lower end on said bearing and at its middle portion bearing against said part of said beam, 120 and means for forcing the upper end of said key transversely toward the adjacent part of said head and securing it.

12. In a brake-beam, the combination with a brake-head having a slot in the lower portion of its back, the forwardly facing wall 125 of which slot affords a fixed bearing, a part

of the beam on which said head is mounted, 5
an independent substantially vertical key in
the back of said head fulcrumed at its lower
end on said bearing and at its middle portion
bearing against said part of said beam,
and means for forcing the upper end of said
key transversely toward the adjacent part
of said head and securing it, said means
comprising a bolt extended through a por- 10
tion of said head and the end of said key

and a nut on said bolt for forcing said end
of said key toward said portion of said head.

Signed at New York, in the county of
New York, and State of New York, this
18th day of January, A. D. 1913.

SETH A. CRONE.
